United States Patent Office

Des. 177,540
Patented Apr. 24, 1956

177,540

HOUSING FOR AN X-RAY TUBE AND BLOWER OR SIMILAR ARTICLE

William G. Waggoner, Elm Grove, and Reimann L. Stroble, Milwaukee, Wis., assignors to General Electric Company, a corporation of New York

Application May 13, 1955, Serial No. 35,979

Term of patent 14 years

(Cl. D61—1)

FIG. 1.

FIG. 2.

Fig. 1 is a front perspective view of a housing for X-ray tube and blower or similar article, showing our new design; and

Fig. 2 is a rear perspective view thereof.

We claim:

The ornamental design for a housing for X-ray tube and blower or similar article, as shown.
